FIG. 3

UNITED STATES PATENT OFFICE

2,159,260

ENVELOPE OPENING MACHINE

Edward J. Dummer and Azel Gay, Rochester,
N. Y., assignors to Multipost Company, Roches-
ter, N. Y., a corporation of New York

Original application December 24, 1936, Serial
No. 117,486. Divided and this application
October 13, 1938, Serial No. 234,833

3 Claims. (Cl. 164—61)

Our present invention relates to paper feeding and cutting machines and more particularly to envelope or mail opening machines of the type in which the letters either stacked or singly may be run rapidly through and one of their marginal edges neatly slit to just remove the fold without injuring the contents, and it has for its object to provide a simple, efficient and improved machine of this character that may be conveniently operated at high speed and capacity and yet with surety of accurate performance. This application is a division of our prior application, Serial No. 117,486, filed December 24, 1936 and allowed July 21, 1938. The present improvements are directed in part and more particularly, so far as this application is concerned, to the formation of an edge guide that directs the envelopes in the cutting plane of the knives so that one fold of the envelope will be completely removed to open it along its entire extent but without endangering its contents. To these and other ends, the invention resides in certain improvements and combinations of parts, all as will be herein-after more fully described, the novel features being pointed out in the claims at the end of this specification.

In the drawings:

Fig. 1 is a front elevation of a letter opening machine constructed in accordance with and illustrating one embodiment of our invention;

Fig. 2 is a top plan view thereof;

Fig. 3 is an enlarged front view of the knives and the edge guide, with the intervening parts removed;

Fig. 4 is an enlarged detail sectional end view of the presser feet and edge guide, with intervening parts omitted, and

Fig. 5 is a view similar to Fig. 4 illustrative of the action of the presser feet on a passing envelope.

Similar reference numerals throughout the several views indicate the same parts.

To properly disclose the structure and function of our improved edge guide, it is necessary to describe in general the mode of operation of the entire machine omitting, however, details shown and described in the parent application that do not directly affect the mode of operation of such guide.

Referring more particularly to the drawings, 1 indicates a preferably cast base having end walls 1^a and a partition-like central framework 2 rising therefrom. At the front is suitably secured a cover plate 3 and at the rear a cover plate 4 together constituting a casing within which the interior mechanism is housed. At the front a shelf-like plate 5 constitutes the bed along which the envelopes are fed and operated upon. Rising from the rear wall of this bed plate at the left end thereof in Fig. 1 is a flange 6 constituting a

general rear guide wall. A transversely extending vertical plate 7 has a flange by which it is secured to the frame 2 at 8 and constitutes a gate beneath which the envelopes are fed. They are stacked on this left hand or feed end of the bed plate 5 in an inclined pile, the regularity of which is established by the guide wall 6 and the said gate 7. The downward inclination of the feed of the lower envelope is established by a shed 9 secured to the table by a screw 10 passing therethrough and into a lug 11 on the adjacent base end 1^a.

At the right hand end of the table and beneath the same to run from front to rear, the frame 2 is provided with a suitable drive shaft 13 (shown only in dotted lines in Fig. 1) that is operated by any suitable means, such as a motor in the base. At its forward end it carries a lower slitting disk or rotary knife 20, the cutting edge of which is in the general plane of the back guide wall 6. On the same shaft and forwardly of the knife is a grooved drive pulley 22. Another grooved idler pulley 23 is mounted on a stud 24 on the frame partition 2 and over the two pulleys passes an endless feed belt 25. This feed belt is preferably of rubber and circular in cross section. Its upper reach 26 travels in slot 27 on the bed plate 5 and projects just partially above the same so as to take sure frictional contact with an envelope on the bed while the latter is still maintained in a substantially flat condition.

Above the bearing of the lower knife and pulley shaft 13 is a bearing 28 on the frame 2 containing a stud shaft 29. On the outer or forward end of this stud is a hub against which there is clamped by a nut 31 an upper companion slitting knife 32 cooperating in the overlapping manner best shown in Figs. 3 and 4 with the driven knife 20. This shaft 29 is spring pressed axially from the rear so that it is maintained close against lower knife 20 and is frictionally driven therefrom.

As best shown in detail in Fig. 3, an extension 36 on the end of the back plate or guide 6 of the bed plate 5 projects toward the knives and has a 45 tapered end 37 that enters between them at their intersection running as closely as possible to the bite or cutting point of the blades. This extension is V-shaped in cross section, as also shown in the other figures, but the bottom at the inside 50 apex is definitely flat, as indicated at 38, lies in the plane of the guide wall 6 and this plane is sufficiently back of the cutting plane defined by the contacting surfaces of the knives to cut off the fold of the envelope edge back the desired 55 distance. The lower plate 39 of the edge guide inclines downwardly outwardly to contact with the bed plate 5 while its longitudinal projection toward the feed end of the machine is given a compound curve into which the lateral inclination 60

merges. It thus also inclines downwardly at the receiving end to meet the surface of the bed plate and forms a ramp portion 40 up which the envelopes slide to enter the edge guide against the wall 38. The upper plate of the V at the corresponding end has a share portion 41 where it joins the plate 6 for a similar purpose.

As so far described, in operation, the undermost letter of a stack squared against the back wall 6 10 and the gate 7 touches or is urged by the operator against the belt 25. It is carried under the gate and the frictional hold of the belt thereon causes it to overcome the retarding influence of a spring finger 42 on the far side of the gate having a 15 notch therein to accommodate the belt at other times. The finger has a rounded lower edge which, however, arrests the envelope next above until the first one, whose frictional contact might otherwise carry such upper envelope with it, has 20 passed on. This adjacent or following one in turn contacts the superior friction of the feed belt and is next fed forward. The latter carries each envelope along the edge guide through the knives which slit the fold thereof and then passes it out 25 at the right end of the machine in opened condition.

The said retarding finger 42 is mounted on a shaft 44 extending between the securing flange and a front flange 45 of the gate plate 7 and is pressed downwardly by a spring 46 coiled about such shaft. A lug 47 on the finger carries a stop screw 48 that bears against a lug 49 on the gate to limit the downward thrust of the finger with reference to the belt and to the nature of the 35 mail matter that is passing through.

It is, of course, important that as the envelope enters the knives its edge should be firmly and evenly against the wall 38 of the edge guide so that the fold thereof will be uniformly and 40 evenly sheared off to exactly the desired extent. This is insured partly by the converging of the travel of the upper reach 26 of the feed belt 25 and partly by a relatively cocked arrangement 45 of its pulleys whereby such reach twists or rotates on its own geometrical axis toward the knives as it passes from the one pulley to the other in the feeding direction. Its frictional effect on the envelope is, therefore, both to convey it in a straight path and to urge it laterally toward the knives 50 and against the edge guides 36.

At the cutting point, the envelope is held to the knives in conjunction with the combined action of the belt and guide 36 by compressor feet 50 and 51, shown in Figs. 1, 2, 4 and 5. These 55 are jointly notched at 52 to span the feed belt and are pivoted upon a stud 53 projecting from the vertical frame piece 2. The inner foot 50 is provided with a lug 54 engaging beneath the foot 51. The latter is pressed downwardly by a spring 60 55 coiled about the stud so that through the lug it also presses down companion foot 50. The latter, however, is provided with a stop screw 56 engaging a lug 57 on the frame to regulate the maximum depression of both feet with respect 65 to the belt and the envelope carried thereon. Also, it will be obvious that, while foot 51 may rise independently, the lifting of inner foot 50 raises outer foot 51 with it if the latter is not already above contact with the lug 54. The purpose of this is best illustrated in Fig. 5. Inner foot 50 rides on the thin edge portion of the envelope A into which its contents B do not project and cooperates with the guide 36-38 to 70 present the edge fold squarely to the knives. Foot 75 51 rides on the bulged body of the envelope exert-

ing enough retarding effect to keep it from slew-ing around when the resistance of the knives is met and with an extremely bulky envelope rises independently, as described. The under side of the contact portion of foot 50 is preferably inclined downwardly and rearwardly toward the cutting plane.

In an envelope handling machine of the character described, the letters are stacked and fed from a precise relatively angularity of the bed 10 and back plate and only as they reach the vicinity of the cutters are they directed into the V-guide. This V-guide is in the nature of an attachment and by providing the ramp 40, as set forth in the claims, the bottom letter of the pile is eased up- 15 wardly from the level of the bed to an elevation above the latter where the knives are arranged so as to take it at a proper cutting point from the belt that is also raised above the level of the bed. A thin envelope goes to the flattened apex of the 20 guide for which the machine is adjusted, and a thick envelope also goes to the same point of contact and is cut to precisely the same extent in precisely the same manner, which it would not do were it not for the wall 38. Furthermore, the 25 urging of the envelope toward the guide constitutes a valuable part of this combination because, with either a thin envelope or a thick envelope, the flattened apex of the guide permits it to bulge under this pressure, which is desirable both for 30 the efficient action of the knives and for protecting the contents.

We claim as our invention:

1. In an envelope opening machine, the combination with a bed plate, a knife arranged angularly thereto and means for feeding envelopes along the bed, of an edge guide for the envelopes associated with the knife to direct the edge of an envelope in the cutting plane thereof, said edge guide embodying a V-shaped portion next adjacent to the knife and a ramp portion extending longitudinally of the bed in rear of the V-shaped portion forming an incline on which the body of the envelope rides and is elevated in the direction of feed as it approaches the knife. 45

2. In an envelope opening machine, the combination with a bed plate, a knife arranged angularly thereto and means for feeding envelopes along the bed and at the same time urging them laterally toward the knives, of an edge guide for the envelopes associated with the knife to direct the edge of an envelope in the cutting plane thereof, said edge guide embodying a V-shaped portion next adjacent to the knife, the lower plate of which V is inclined transversely to the bed, and the bottom of which at the apex presents a distinctly flat inner guiding surface. 55

3. In an envelope opening machine, the combination with a bed plate, a knife arranged angularly thereto and means for feeding envelopes along the bed and at the same time urging them laterally toward the knives, of an edge guide for the envelopes associated with the knife to direct the edge of an envelope in the cutting plane thereof, said edge guide embodying a V-shaped portion next adjacent to the knife, and a ramp portion forming an incline on which the body of the envelope rides as it approaches the knife, the lower plate of the V portion being inclined transversely to the bed and the bottom thereof at the apex being formed to present a distinctly flat inner guiding surface. 60
